US00D742565S

(12) **United States Design Patent**
Hanson et al.

(10) **Patent No.:** **US D742,565 S**
(45) **Date of Patent:** **** Nov. 3, 2015**

(54) **SIDE LIGHT OF A TRUCK**

(71) Applicant: **Caterpillar Inc.**, Peoria, IL (US)

(72) Inventors: **Eric J. Hanson**, Valparaiso, IN (US);
Gregory Miller, Rochester, MI (US);
Joseph F. Denatale, Greensboro, NC
(US)

(73) Assignee: **Caterpillar Inc.**, Peoria, CA (US)

(**) Term: **14 Years**

(21) Appl. No.: **29/478,445**

(22) Filed: **Jan. 6, 2014**

Related U.S. Application Data

(62) Division of application No. 29/439,606, filed on Dec. 13, 2012, now Pat. No. Des. 697,242, which is a division of application No. 29/381,451, filed on Dec. 20, 2010, now Pat. No. Des. 675,757.

(57) **CLAIM**

The ornamental design for a side light of a truck, as shown and described.

DESCRIPTION

FIG. 1 is a front left perspective view of the truck including a side light showing our new design;

FIG. 2 is a front left perspective view of the side light in FIG. 1;

FIG. 3 is a left view of the side light in FIG. 1;

FIG. 4 is a right view (behind the side light) of the side light in FIG. 1;

FIG. 5 is a top view of the side light in FIG. 1;

FIG. 6 is a front view of the side light in FIG. 1;

FIG. 7 is a back view of the side light in FIG. 1; and,

FIG. 8 is a bottom view of the side light in FIG. 1.

The broken lines shown in FIG. 1 illustrate environmental structure and form no part of the claimed design.

1 Claim, 8 Drawing Sheets
